UNITED STATES PATENT OFFICE

ALOYS SUMBS, OF SAUK RAPIDS, MINNESOTA

INDICATOR

Application filed May 18, 1931. Serial No. 538,362.

This invention relates generally to indicators and more particularly to new and useful improvements in indicators for use on wood grinders in paper mills and has for some of its most important objects to provide a device of this character which will be comparatively simple in construction, strong, durable, efficient and reliable in use, compact and which may be manufactured at low cost.

10 All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation showing a pair of indicators in accordance with this invention mounted in position on a wood grinder.

Figure 2 is a view in front elevation of one of the indicators.

Figure 3 is a view in vertical section through the device.

Figure 4 is a sectional view taken substantially on the line 4-4 of Figure 3.

Figure 5 is a sectional view taken substantially on the line 5-5 of Figure 3.

30 Figure 6 is a sectional view through the grooved pulley or spool.

Figure 7 is a view in top plan of the device.

Figure 8 is a detail view partially in section and partially in plan of the attaching bracket.

Referring now to the drawings in detail, it will be seen that the reference numeral 1 designates a substantially annular housing having detachably secured on its front a cover plate 2 which constitutes a dial, as will be more fully hereinafter explained. At its rear end the housing is closed and is provided with a peripheral flange 3 having notches or recesses 4 therein for the reception of the keepers 5 through the medium of which a cover 6 is detachably secured on the rear end of the housing 1. The cover 6 has secured thereon, as by screws 7 (see Figure 8), a bracket 8 for mounting the indicator in position on the

grinder 9, as illustrated to advantage in Figure 1 of the drawings.

Spaced metallic frames or plates 10 and 11 are mounted in the housing 1 in spaced relation to the front and rear of said housing. A 55 shaft 12 is journaled in the cover 2 and the plate 10, said shaft extending rotatably through the cover 2, a ball bearing 13 being provided therefor centrally in the cover. A pointer 14 is fixed on the outer end portion of the shaft 12. A shaft 15 is journaled in the plates or frames 10 and 11 and has one end disposed adjacent the cover 2 and gears 16 and 17 are fixed on the shaft 15 on opposite sides of the plate or frame 10. The gear 16 meshes with a comparatively small gear 18 which is fixed on the shaft 12 between the cover 2 and the plate or frame 10.

A shaft 19 is journaled in the plates or frames 10 and 11 and the rear wall 20 of the housing 1, said shaft extending into the cover 6 on the rear end of the housing. A comparatively large gear 21 is loosely mounted on the shaft 19 between the plates or frames 10 and 11 and meshes with the gear 17. A ratchet wheel 22 is fixed on the shaft 19 adjacent the gear 21 for rotation with said shaft 19. A pawl 23 is pivotally mounted on one side of the gear 21 and is maintained in engagement with the ratchet disk or wheel 22 by a suitable 80 spring and in this manner the gear 21 is operatively connected with the ratchet wheel for actuation in one direction thereby.

A spring 24, such as a block spring, encircles the shaft 19 between the plate or frame 11 and the rear end wall 20 of the housing 1 and has one end secured to the shaft 19 and its other anchored to the housing for rotating the shaft 19 in one direction, as will be understood. The end portion of the shaft 19 which is disposed within the cover 6 has fixed thereon a peripherally grooved or channelled pulley 25 upon which a chain 26 is windable, one end of the chain being anchored to the pulley, as clearly seen in Figure 6 of the drawings. From a consideration of Figure 6 it will also be seen that the end portion of the shaft 19 upon which the pulley 25 is mounted is flattened on opposite sides to prevent rotation of the pulley relative to said shaft. The 100

chain 26 is operable through an opening provided therefor in the cover 6 and has its other end connected to the outer end of the rod 27 which projects from the pocket 28 of the wood grinder 9 upon which the indicator is mounted. It is understood, of course, that an indicator in accordance with this invention is mounted on each of the pockets 28 of the wood grinder.

10 The housing 1 is substantially leakproof for the reception of a suitable lubricant and is provided with removable screw plugs 29 and 30 in its top and bottom, respectively, the plug 29 providing means for filling the housing with a lubricant and the plug 30 providing means for draining the housing. The plates or frames 10 and 11 are secured together in spaced relation to each other through the medium of the screws 31 having spacing sleeves 32 thereon between the frames or plates.

15 In use, as the grinding of the wood in the machine proceeds normally, the rods 27 are drawn inwardly in the usual manner with the result that the chain is unwound from the pulley 25, thus actuating the pointer 14 through the various shafts, gears and the pawl and ratchet, as will be understood. This operation of the device winds the spring 24. Thus, by observing the pointer 14 relative to the dial which is constituted by the cover 2, it can be determined whether or not the wood is being ground. After the wood in the pockets has been ground and said pockets are refilled, the rods 27 are raised in the usual manner and the spring 24 rotates the shaft 19 in the opposite direction to rewind the chain 26 on the pulley 25. The pointer 14 is reset and the indicator is then ready for 20 the next grinding operation. The spring 24 is under slight tension when the grinding operation is begun and when the chain 26 is wound on the pulley 25. It will be understood that only the shaft 19 and the ratchet wheel 22 are rotated when the spring 24 re-winds the chain on the pulley. This is accomplished through the medium of the ratchet wheel 22 and the pawl 23.

25 It is believed that the many advantages of an indicator in accordance with this invention will be readily understood, and although the preferred embodiment of the invention is as illustrated and described, it is to be understood that changes in the details of construction and in the combination and arrangement of parts may be resorted to which will fall within the scope of the invention as claimed.

30 What is claimed is:—

60 The herein described indicator for apprising an operator when the wood in a pocket of a wood grinder is approaching exhaustion, consisting essentially of a housing having a dial on its face, a shaft journaled in the front wall of said housing and equipped in front

of said wall with a pointer for cooperation with said dial, a shaft journaled in the back wall of the housing and extending in rear of said wall, a spring in the housing and connected with the last named shaft and also connected with the housing and coiled about the shaft and adapted to be put under tension by turning of the shaft in one direction and also adapted to turn the shaft in the opposite direction, gearing disposed in said housing and interposed between the last named shaft and the first named shaft; the said housing being oil-tight and having normally enclosed means for the entrance of lubricant into the same, a hollow cover connected to the back wall of the housing and receiving the rearwardly extended portion of the second named shaft and equipped with a bracket for the mounting of the indicator on a grinder, said hollow cover also having an opening for the passage of a cable, and a pulley mounted on the rearwardly extended portion of the second named shaft and disposed in said hollow cover and adapted for the connection of the said cable.

90 In testimony whereof I affix my signature.
ALOYS SUMBS.
